UNITED STATES PATENT OFFICE

2,325,487

STEAM HEATING SYSTEM

James A. Donnelly, Brooklyn, N. Y.

Application February 21, 1941, Serial No. 380,015

14 Claims. (Cl. 237—9)

My invention relates to steam heating systems and more particularly to that class of steam heating systems in which a circulation of steam thru the system is maintained by the connection of the return with a vacuum pump, such a system being disclosed in my patents, No. 974,245 and/or No. 974,246, both issued November 1, 1910, and/or No. 1,681,725, issued August 21, 1928.

A chief object of my invention is to provide a steam heating system, to meet any heating requirements, that is efficiently and economically operable, and that is susceptible of low manufacturing and installation cost because of the small number and the manufacturing simplicity of its operative and controlling features.

A chief object of the invention is to provide such a steam heating system that gives a uniform distribution of steam to the parts of the system where the condensation of the steam takes place, irrespective of their distance from the source of supply, and is quickly responsive to the varying requirements for heat in condensing parts of the system.

Another object of the invention is to provide a steam heating system in which the steam may be maintained at predetermined variable pressures in the supply pipe and the branch pipes while the pressure of the system may be reduced or varied, thereby causing the introduction of less or different amounts of steam, as required by the demand for heat caused by the outside prevailing weather condition.

A further object of the invention is to provide a steam heating system in which, when the system is operated under an on-and-off timing schedule with the periods of on-and-off according to the outside weather requirements, a sufficient supply of steam is maintained so that, while all the radiators cool completely yet the steam main and branches remain hot, the foregoing result being accomplished either manually or automatically, by introducing air into the return system in varying quantities while constant temperature and pressure of the steam are maintained beyond the group or branch main orifices by means of a thermostatic or pressure-operated reducing valve.

Another object is to provide a method of drawing more or less steam into a steam heating system by increasing or decreasing the vacuum in the return of the system.

Another object of the invention is to increase the longevity of the system by maintaining the temperature of the expansion devices substantially constant during the entire period of the

use of the system, therefore maintaining these devices in the expanded condition.

5 A further object is to provide a quicker response in the steam condensing parts of the system to either manual or automatic control of the steam supply of the system by maintaining the supply main and branches and/or risers at the supply steam temperature of the system.

10 A further object is to provide in a vacuum-pump steam heating system means for controlling, manually or automatically, the vacuum in the return system, either at the outlet of the entire return system or in a part thereof, by means responsive to the outside weather particularly the cooling effect of the outside air.

15 A further object is to provide a steam heating system in which the flow of steam to the radiators is proportioned by means of fixed orifices and the flow in the return system is balanced by similar fixed orifices.

20 While reference has been made to outside temperature as controlling the system, atmospheric conditions in general, including wind velocity, moisture content of the air and even atmospheric 25 pressure may affect the thermostat and have an influence on the control of the system; however, admission of air in approximate correspondence with or in approximate proportion to and directly related to changes of temperature is believed to 30 be sufficiently accurate for the purpose of the claims and description.

My improved steam heating system may be so subdivided as to supply the needs of the different portions of the distributing mains, pipes, risers, 35 etc., whereby it is delivered into the radiators only in the exact quantity required, the circulation thus produced insuring the exact predetermined results as to room temperature and, at the same time, permitting said room temperature 40 to be varied to the desired extent at will, while not exceeding the predetermined maximum temperature required. By the employment of exactly proportioned fixed orifices, steam is so thoroughly subdivided and accurately distributed among all 45 of the headers, risers and branch pipes, that each radiator may be definitely supplied with the required steam, whereby uniform temperature is automatically assured thruout the building, and the return system is balanced proportionally with fixed orifices, thus enabling a large steam heating system to be operated perfectly as a vacuum return line system. By setting the vacuum pump at the outlet for a uniform rate of action suitable to the most severe outside weather conditions and admitting air to the return system automatically

by means of an outside thermostat a perfectly operating automatic system is provided with simple parts.

By almost but not quite balancing the pressure in the return system with the pressure at the supply pipe, sufficient steam may be admitted to any desired proportion of the system to keep the supply main, branches and/or risers hot while the radiators are cool.

Other objects will appear as the description 10 proceeds.

Reference is made to the drawings in which Figure 1 is a schematic showing of my improved system.

Figure 2 is a vertical section of a liquid thermostatic valve control.

Figure 3 is a detail view, approximately actual size, of a fixed orifice fitting, the same being broken away to show the internal construction on a plane determined by the axis of the pipe connected thereto, and the axis of the valve stem.

A steam main 10 may be connected with a constant source of steam supply, preferably at atmospheric pressure and at a temperature of 212 degrees Fahrenheit, and may have any desired number of branch mains 11, 12, 13, 14, 15, 16, and 17, each of which leads to a group of radiators; branch 15 to radiators 18, 19, 20, 21, 22, and 23; branch 16 to radiators 24, 25, 26, 27, 28, and 29; and branch 17 to radiators 30, 31, 32, 33, 34, and 35. The return pipes from the first group of radiators are connected with the branch return pipe 36, the return pipes from the second group of radiators are connected with the branch return pipe 37, and the return pipes from the third group of radiators are connected with the branch return pipe 38. The branch return pipes 36, 37, 38, 39, 40, 41, and 42 from the various groups of radiators lead into the return main 43 which outlets into a vacuum pump 44, which is preferably set for uniform action.

A thermostatic valve 45, which may be any suitable valve such as the Sarco type 2430, is placed in the main 10 at the inlet and the temperature pipe 96 of the valve is connected with any of the branch pipes beyond the orifices, as shown, to branch pipe 11 beyond an orifice 46 therein. The steam at the inlet to the main 10 is therefore maintained at a constant predetermined temperature, preferably 212 degrees Fahrenheit, and at a constant predetermined pressure, preferably atmospheric pressure.

Orifices 48, 47, 48, 49, 50, 51, and 52 in the branches 11 to 17, inclusive, are fixed orifices predetermined to the proportional steam requirements of each branch. Orifices 53, 54, 55, 56, 57, and 58, in the subbranch pipes to the radiators 18, 19, 20, 21, 22, and 23 are fixed orifices graduated to meet the steam requirements of the respective radiators. Similarly orifices 59, 60, 61, 62, 63, and 64 are fixed orifices proportioned to the steam requirements of radiators 24, 25, 26, 27, 28, and 29, respectively, and orifices 65, 66, 67, 68, 69, and 70 are fixed orifices also proportioned to the steam requirements of the radiators 30, 31, 32, 33, 34, and 35 respectively.

The Donnelly Patent 1,876,174 shows in Figures 6 to 11 at 82 and 97 an adjustable orifice adapted to this purpose, when once adjusted it is constant.

The radiators are of any known form and design adapted to the heating requirements and are positioned in accordance with accepted steam engineering practice.

Beyond the radiator outlets there are positioned in the outlet pipes fixed orifices 71, 72, 73, 74, 75, 76, 77, 78, 79, 80, 81, 82, 83, 84, 85, 86, 87, and 88, which may be similar respectively to the orifices 53 to 70, inclusive, seriatim.

In the return branch pipes 36, 37, 38, 39, 40, 41, and 42 are placed respectively fixed orifices 89, 90, 91, 92, 93, 94, and 95, and which may be similar respectively to the fixed orifices 46 to 52, seriatim.

It is now apparent that the steam heating system above described is adapted to feed steam at atmospheric pressure and to deliver constant proportional quantities of steam at the steam-condensing parts of the system to meet the requirements of any radiator by means of the graduated fixed orifices in the branches and/or risers, and similarly frictionally balanced to cause proportional flow in the return branches and/or risers and the return main by the vacuum in the return main produced by the constant action of the vacuum pump under most severe outside weather conditions.

I now describe means whereby the system may be automatically controlled for variations in the requirements for heat by means of simple apparatus: A thermostat 101 may be mounted on a bracket 105 over the end of an air inlet pipe 102 which has an inlet 103 into the return main 43 in the suction of the vacuum pump 44. From the top of the dome of the thermostat 101 is a depending arm 106 which supports a heat expansible container 107 which may contain a liquid such as ether or chloroform mixed with water, sensitive to temperature changes, and from which depends a conical valve 108 restricting and sealing the valve seat 104 at severe outside weather and opening proportionally to temperature rises. In other words the thermostat 101 decreases the vacuum as the outside weather becomes milder. A manual control 125 of the inlet 103 may be used when and if desired, and similar manual control of the inlets 118, 119, and 120, so that any desired quantity of steam may be drawn into a part of the system or merely sufficient steam to keep the supply main and branch mains and/or risers hot.

Figure 3 illustrates a fitting which by change of the size of orifice may be used as the fixed orifice fitting indicated in the drawings, Figure 1, by reference characters 46 to 95.

Referring to Figure 3, the fitting comprises a hollow body or casing 125 connected to the steam pipes A and B by threaded connections 126 in any suitable manner. This casing has a transverse partition 127 with an offset 128, having therein a circular hole or opening 129 into which is pressed or inserted a disc 130 having an opening 131 of suitable size according to the above description. The opening 129 is also shown as provided with a circumferential seat 132 adapted to receive and cooperate with a valve 133 mounted on a stem 134 which may be screw threaded and operated by a handle 135. It should be understood that this Figure 3 is merely explanatory of a fitting which may be used for the purpose indicated, in connection with the description relating to reference characters 46 and 95 and is no part of the invention.

The purpose of the valve 133 and its seat 132 is to permit any branch pipe or branch main to be closed for cutting off part of the system as in the instance of repairs or alterations and not to change the capacity of the orifice 131 which is intended to be a fixed orifice and predetermined

in the system as designed, the valve 133 being normally wide open.

In systems where the outside weather conditions vary greatly at different parts of the steam heating system, thermostats 101 may be mounted, at the end of air inlet pipe 110 having an inlet 118 to the branch return behind the orifice 91, at the end of pipe 111 having an inlet 119 behind the orifice 90, at the end of pipe 112 having an inlet 120 behind the orifice 89, at the end of pipe 113 having an inlet 121 behind the orifice 95, at the end of pipe 114 having an inlet 122 behind the orifice 94, at the end of a pipe 115 having an inlet 123 behind the orifice 93, and at the end of a pipe 116 having an inlet 124 behind the orifice 92.

Having shown and described a preferred embodiment of my invention and realizing that, in view of my disclose many substitutions, additions, or omissions of parts, or rearrangement of parts, will readily occur to those skilled in the art, I do not limit myself to the exact disclosure herein.

I claim:

1. A steam heating system wherein there are associated and combined, a source of steam supply, a steam main, a plurality of branching mains respectively opening from the steam main at different distances from the source of steam supply, a plurality of groups of radiators of which a separate group is connected with each of the branching main and receives steam therefrom, fixed orifice means between the several radiators of each group and the respective branching mains to cause the steam therefrom to be supplied to the radiators in predetermined proportioned quantities, means in communication with the source of steam supply for initially supplying the system as a whole with steam of a predetermined quantity required for all of the radiators thereof, means having fixed orifice means arranged in the respective branching mains between their connection with the radiators and the steam main and each such orifice proportioned to insure the passage of the predetermined quantity of steam required by the radiators of the corresponding group, a return system comprising branches from the radiators, return branch mains, and a return main, and orifice means in said return branch mains and return main proportioned to those in the supply system whereby a balanced flow is produced thruout the system, and a vacuum pump connected with the outlet of the return system.

2. The subject matter of claim 1 and further, means for introducing air in quantities approximately in direct proportion to outside temperatures into the return system thereby reducing the vacuum in the return main and hence the flow in the radiators as the outside temperature rises and increasing the vacuum in said return main and the flow through the radiators as the outside temperature is reduced.

3. A heating system as per claim 1, for heating an enclosure, said system further comprising temperature controlled means exposed to the outside atmosphere and an air valve controlled thereby and operatively connected thereto for introducing air in predetermined and variable quantities into the return system, said air valve opening in response to increase of said temperature, the quantity of air thus admitted being directly related to and in approximate proportion to the said atmospheric temperature.

4. A heating system as per claim 1, for heating an enclosure, said system further comprising a thermostat, exposed to the outside atmosphere

and controlled by the temperature of the surrounding air and a valve controlled by the thermostat to open and close in approximate conformance to the increase and decrease respectively of said temperature, for introducing air in predetermined and variable quantities into the return system, the maximum quantity of air being introduced when said temperature is relatively high and the minimum when said tem-

perature is relatively low thereby the flow of steam through the radiators is reduced at high temperatures of the outside atmosphere and increased at low temperatures of said atmosphere.

5. A heating system as per claim 1, for heating an enclosure, said system further comprising an air pipe connected with the return system, and open to admit air to said return system an air valve controlling the passage of air through said pipe and a thermostat exposed to the outside air and controlled by its temperature and connected to and automatically controlling said valve.

6. A heating system as per claim 1 for heating an enclosure, said system further comprising an air pipe connected with the return system and extending outside the building and open for the admission of air, a valve seat through which the air enters said pipe, a valve cooperating with said seat, and a thermostat responsive to outside weather conditions and having an actuating connection to said valve.

7. A heating system as per claim 1 for heating an enclosure, said system further comprising an air inlet pipe connected with the return system and terminating outside the building where it has a vertical portion, an opening comprising a valve seat in the end of said pipe, a valve in said opening, and a thermostat exposed to the outside air and controlled thereby, said thermostat being adjacent said opening, said thermostat comprising a liquid expansion container which supports and actuates said valve.

8. A heating system as per claim 1 for heating an enclosure, said system further comprising means for introducing air in predetermined and variable quantities into the branch mains of the return system, said quantities being approximately in direct proportion to the temperature of the outside air and being varied in direct relation to the changes of said temperature.

9. A heating system as per claim 1 for heating an enclosure, said system further comprising means for introducing air in predetermined quantities variable in approximate proportion to the cooling effect of the outside atmosphere and in direct relation thereto, said air entering into the branch mains of the return system between the fixed radiator orifice means and the branch main orifice means in the return system.

10. A heating system as per claim 1 for heating an enclosure, said system further comprising a thermostatically operated valve controlled by the temperature of the surrounding atmosphere and located in the supply pipe and connected with a branch supply main at a point between the orifice means in said branch supply main and a radiator fixed orifice means in a pipe connecting the radiator with said branch main, and controlling the amount of steam admitted thru the supply pipe.

11. A steam heating system for an enclosure, in which system there are associated and combined, a source of steam supply, a steam main, a plurality of branching mains respectively opening from the steam main at different distances from the source of steam supply, a plurality of groups of radiators of which a separate group is connected with each of the branching main and receives steam therefrom, fixed orifice means between the several radiators of each group and the respective branching mains to cause the steam therefrom to be supplied to the radiators in predetermined proportioned quantities, means in communication with the source of steam supply for initially supplying the system as a whole with steam of a predetermined quantity required for all of the radiators thereof, means having fixed orifice means arranged in the respective branching mains between their connection with the radiators and the steam main and each such orifice proportioned to insure the passage of the predetermined quantity of steam required by the radiators of the corresponding group, a return system comprising branches from the radiators, return branch mains, and a return main, and orifice means in said return branch mains and return main proportioned to those in the supply system whereby a balanced flow is produced thruout the system, and a vacuum pump connected with the outlet of the return system.

groups of radiators of which a separate group is connected with each of the branch mains to receive steam therefrom, means in communication with the source of steam supply for initially supplying the system as a whole with steam of a predetermined quantity required for all of the radiators thereof, means having fixed orifice means arranged in the respective branch mains between their connection with the radiators and the steam main and each such orifice proportioned to insure the passage of the predetermined quantity of steam required by the radiators of the corresponding group, a return system comprising branches from the radiators, return branch mains and a return main, and orifice means in said return branch mains and return main proportioned to the orifices in the supply system whereby a balanced flow is produced thruout the system, a vacuum pump connected with the outlet of the return system, and a thermostatically operated valve controlled by the surrounding atmosphere and located in the supply pipe and connected with a branch supply main at a point between the branch orifice in said branch supply main and a radiator connected with said branch main, and controlling the amount of steam admitted thru the supply pipe.

12. A steam heating system for an enclosure, in which system there are associated and combined, a source of steam supply, a steam main, a plurality of branching mains respectively opening from the steam main at different distances from the source of steam supply, a plurality of groups of radiators of which a separate group is connected with each of the branching mains and receives steam therefrom, means in communication with the source of steam supply for initially supplying the system as a whole with steam of a predetermined quantity required for all of the radiators thereof, means having fixed orifice means arranged in the respective branching mains between their connection with the radiators and the steam main and each such orifice proportioned to insure the passage of the predetermined quantity of steam required by the radiators of the corresponding group, a return system comprising branches from the radiators, return branch mains, and a return main, and orifice means in said return branches and said return branch mains proportioned to those in the supply system whereby a balanced flow is

produced thruout the system, a vacuum pump connected with the outlet of the return system, and means for introducing air in predetermined and variable quantities into the branch mains of the return system between the branch main orifice and the orifice means in the return branches, and means for regulating said quantities in approximate proportion to the outside temperature and in direct relation thereto.

- 10 13. In a steam heating system for heating an enclosure, said system comprising a steam supply main connected to a steam supply, a return pipe, steam radiators connected to the steam supply main to receive steam therefrom and to the return pipe, power operated means for creating and maintaining a vacuum in the return pipe, means for admitting air to the return pipe and means exposed to the outside air and controlled by the cooling effect of the outside air and a valve operatively connected thereto for determining the quantities of air admitted whereby said quantities are approximately proportional to the cooling effect of the outside air and changed in direct relation to the changes of temperature, thus reducing the vacuum in the return pipe as the outside temperature is increased and increasing the vacuum in the return pipe as the temperature of the outside air is decreased.
- 20 14. In a steam heating system for heating an enclosure, said system having a steam supply main connected to a steam supply, a return pipe, steam radiators connected to the steam supply main to receive steam therefrom and to the return pipe, to discharge steam and water therethrough to provide a flow of steam to and through the radiators, power operated means for creating and maintaining a reduced pressure in the return pipe, means, including a thermostatic control exposed to the outside air and thus directly controlled by the cooling effect of the outside air for reducing the vacuum in the return pipe and hence the flow of steam through the radiators as the outside temperature rises and increasing said vacuum as the outside temperature falls, whereby the flow of steam through the radiators and the heating effect of the radiators is varied and maintained in approximately inverse relation to the outside temperature.
- 30 50 JAMES A. DONNELLY.
